LAMP SHADE MOUNTING

William N. de Sherbinin, Brookfield, Conn.

Application April 29, 1950, Serial No. 159,085

5 Claims. (Cl. 240—138)

1

This invention relates to electric lighting fixtures and more particularly pertains to lamps of the type having a shade which is attached to and supported on the electric light bulb of the lamp.

Heretofore, in lamps of the type referred to, the shade has been supported on the bulb by an adapter which is assembled from a plurality of separate pieces. For example, the bulb engaging portion is in several pieces and the shade engaging parts are separately produced, and all the pieces are secured together to form the adapter. This is time consuming, complicated and expensive.

The present invention overcomes these disadvantages and provides an adapter for securing a lamp shade to an electric light bulb which is made in one piece and yet adequately performs all the functions of the previous multi-piece type.

The invention will be understood from the following description when considered in connection with the accompanying drawings forming a part thereof, and in which:

Fig. 1 is a perspective view of an adapter embodying the invention, shown supporting a plastic lamp shade on an electric light bulb;

Fig. 2 is a sectional view taken on line 2—2 of Fig. 1;

Fig. 3 is a sectional view taken on line 3—3 of Fig. 1;

Fig. 4 is a view in elevation, on an enlarged scale, showing the manner in which the shade engaging portion of the form of the adapter shown in Figs. 1 to 3, is formed;

Fig. 5 is a top plan view of the adapter, shade and bulb shown in Fig. 1 with a modification in the shade;

Fig. 6 is a perspective view of another form of adapter embodying the invention.

Fig. 7 is a top plan view of the adapter shown in Fig. 6, on an enlarged scale;

Fig. 8 is a sectional view on line 8—8 of Fig. 7;

Fig. 9 is a view in elevation showing the manner in which the shade engaging portion of the form of adapter shown in Figs. 6 to 8 is formed initially, and

Fig. 10 is a top plan view of the shade engaging portion of the adapter shown in Fig. 9.

Like characters of reference designate the same or similar parts throughout the several views.

Referring to Figs. 1 to 5 of the drawings, reference character 10 designates an electric light bulb mounted in the usual socket, not shown,

2

which is secured to any suitable electric lighting fixture, now shown. The plastic shade 11 has an inwardly projecting flange 12 which constitutes in effect an annulus having diametrically opposed notches 13 in the upper part of the annulus.

The adapter comprises a bulb engaging portion and a shade engaging portion, which, in the form shown in Figs. 1 to 5, specifically engages the annulus 12. As shown, the adapter is made from a single length of wire of sufficient rigidity to retain its shape and of sufficient resiliency to cause it to spring back into position when moved out of position. The bulb engaging portion consists of two loops 14 and 15 which engage opposite portions of the bulb 10 and which are connected by a part of the wire 16 running across the top of the bulb. The outer end of the loop 14 continues upwardly at 17 to a point 18 approximately above the top of the bulb where it is bent at a sharp angle and extends outwardly at 19 to the annulus engaging portion. In like manner, the outer end of the loop 15 continues upwardly at 20 to a point 21 where it is bent at a sharp angle and extends outwardly at 22 to the annulus engaging portion. The parts 19 and 22 are reversed with respect to each other as compared with the parts 17 and 20 with the result that the angles at the points 18 and 21 engage each other and limit the movement apart of the two annulus engaging portions at the upper ends of the parts 19 and 22.

The annulus engaging portion on the part 22 comprises an extension of that part which is bent into the form of an S to provide a recess to receive the annulus 12 of the shade 11. The S includes a return bend 23, Fig. 3, a reversely extending part 24, a return bend 25, and a straight end portion which is diametrically cut at 26 in a plane parallel to the plane of the part 22 to provide two parts 27 and 28, Fig. 4, which then are moved laterally, substantially parallel to the plane of the cut 26, to the positions indicated in dotted lines in Fig. 4 wherein they form a V. The part 27 is also bent downwardly, as best shown in Figs. 2 and 3, until its outer end is at the same elevation as the part 28. Thus a slot is formed between the reversely extending part 24 and the V-shaped parts 27 and 28, which receives the narrow part of the annulus 12 of the shade provided by the notches 13. The annulus engaging portion of the part 19 is formed in the same manner.

To mount the shade 11 on the bulb 10, the loops 14 and 15 are spread apart sufficiently to permit

the bulb to be inserted between them, by moving the bulb upwardly toward the part 16 of the wire which runs across the top of the bulb, or by moving the adapter downwardly on the bulb until part 16 is in contact with the top of the bulb. The annulus engaging portions are then moved toward each other until they can be attached to the annulus 12 of the shade with the V-shaped parts 21 and 28 in alignment with the notches 13 and the reversely extending parts 24 just below the lower surface of the annulus, after which the adapter is released and the parts 19 and 22 will spring apart and the end portions thereof will engage the annulus in the manner illustrated and the shade will be mounted on the bulb. If desired, the adapter can be attached first to the annulus 12 in the manner described, after which the adapter will be mounted on the bulb 10 as described. The annulus engaging portions of the adapter are formed to engage the annulus snugly but detachably to provide a firm grip on the shade. The notches 13 of Figs. 1 to 3 are rectangular in configuration, whereas the notches 29 in Fig. 5 are W-shaped.

In Figs. 6 to 8, the shade 30 is provided with a wire ring 31 at its upper end to which is secured, concentrically of the shade, an annulus 32 by means of three rods 33 welded or otherwise attached to the ring and annulus. The adapter is like the adapter shown in Figs. 1 to 5, excepting for the annulus engaging portions and the adjoining parts 19 and 22 which extend upwardly and outwardly from the angles 18 and 21 instead of just outwardly as in the previous form. The intermediate portion of that part of the wire which extends beyond the part 19 is cut diametrically at 34, and each of the two parts thus formed, is bent outwardly in a plane parallel to the plane of the cut 34, to form a V-shaped section 35. The two sections 35 form a parallelogram beyond which extends the terminal part 36 of the wire. At the inner end 37 of the parallelogram, the wire is bent at an obtuse angle to provide a shoulder upon which rests the lower surface of the annulus 32. The two V-shaped sections are then bent upwardly at the apices of the V's to provide portions which engage the inner circumferential surface of the annulus, and the terminal part 36 is bent outwardly to provide a flange which will assist in retaining the adapter on the annulus and prevent accidental displacement.

The adapter of Figs. 6 to 8 is mounted on the bulb 10 in the manner previously described. The adapter is attached to the shade by moving the annulus engaging portions toward each other until the upwardly extending and terminal portions 36 can be inserted in the aperture of the annulus 32, after which the adapter is released and the V-shaped portions 35 will spring apart and will engage the annulus as shown in Figs. 6 to 8.

The adapter shown in Figs. 6 to 8 can also be utilized to mount a bridge type lamp shade on an

electric light bulb. A bridge type shade is like the shade 30 excepting that the annulus is larger than the annulus 32 and the inner circumferential wall is threaded.

It will be understood that preferred forms of the invention have been selected for illustration and description and that changes can be made in the form of the several parts of the adapter disclosed without departing from the principles of the invention. Accordingly, the invention is not to be limited excepting by the scope of the appended claims.

What is claimed is:

1. An adapter made from wire for securing a lampshade to an electric light bulb comprising a spiral central portion, the spiral including substantially two loops, the bulb being received between the loops, the spiral having end portions which extend tangentially from the spiral and toward each other so as to cross one another, a bend in each end portion at the point of crossing, each bend partially encircling the other end portion, and shade engaging means carried at the free ends of said end portions, the shade engaging means comprising a portion of each free end bent back on itself and a U-bend formed in the bent back portion, part of the bent back portion of the wire being cut longitudinally thereof to provide shade engaging portions separated from each other, the separated shade engaging portions being bent laterally of the axis of the wire substantially in opposite directions to provide contact with the shade at spaced points.

2. An adapter as defined in claim 1 wherein the separated shade engaging portions are at the terminal portions of the free ends of the wire.

3. An adapter as defined in claim 1 wherein the separated shade engaging portions are at the terminal portions of the free ends of the wire and the separated portions are bent apart to form a V.

4. An adapter as defined in claim 1 wherein the separated shade engaging portions are adjacent to but short of the terminal portions of the free ends of the wire.

5. An adapter as defined in claim 1 wherein the separated shade engaging portions are adjacent to but short of the terminal portions of the free ends of the wire and the separated portions are bent apart to form a parallelogram.
